[57] CLAIM

The ornamental design for a flyback lampholder for use on track, as shown and described.

DESCRIPTION

FIG. 1 is a perspective view of the flyback lampholder for use on track showing our design with a lamp shown in phantom;

FIG. 2 is a front elevational view of the flyback lampholder for use on track shown in FIG. 1;

FIG. 3 is a left side elevational view of the flyback lampholder for use on track shown in FIG. 1;

FIG. 4 is a right side elevational view of the flyback lampholder for use on track shown in FIG. 1;

FIG. 5 is a rear elevational view of the flyback lampholder for use on track shown in FIG. 1;

FIG. 6 is a top view of the flyback lampholder for use on track shown in FIG. 1; and,

FIG. 7 is a bottom view of the flyback lampholder for use on track shown in FIG. 1.

The broken lines are shown for illustrative purposes only and form no part of the claimed design.
